UNITED STATES PATENT OFFICE.

RUSSELL K. COLLINS, OF FORT WORTH, TEXAS.

EXPANSION PROCESS AND APPARATUS FOR REFINING OF HYDROCARBONS.

Application filed July 28, 1926. Serial No. 125,502.

This invention relates to improvements in processes and apparatus for the refining of hydrocarbon materials.

The primary object of this invention is 5 the provision of an improved process for the treatment of hydrocarbon oils, by means of which to obtain a better motor fuel, at an increased proportionate yield, which is better in quality than motor fuels produced by 10 conventional processes, because of its ability to operate an internal combustion engine at higher compression.

A further and important object of this invention is the provision of an improved 15 process and apparatus for the production of gasoline or other volatile fuels from hydrocarbon materials, utilizing the expansion process of refining set forth in my co-pending application, Serial #563,136, filed May 20 23, 1922, and by means of which the percentage of unsaturates is efficiently controlled independent of the percent of yield.

A further object of this invention is the provision of an improved apparatus and 25 process for the refining of hydrocarbon materials, by means of which the percentage of yield of fuel can be controlled by reason of changing the concentration of vapors, and by reason of certain safety zones provided in the apparatus wherein the hydrocarbon molecules may be received from certain heating zones during the conversion and recombination treatment of the product.

A further object of this invention is the 35 provision of an improved process for the treatment of hydrocarbon oils, in the vapor phase; the improved treatment being carried forward in a treating zone free of any excessive pressures, wherein all of the vapor, 40 in mass form, is heat treated uniformly by means of a series of uniformly spaced heating elements intercepting the area thru which the vapor is flowing.

A further object of this invention is the 45 provision of an improved process for the refining of hydrocarbon oils in the vapor phase, embodying a novel process of operation and treatment for the purpose of uniformly treating and regulating the heating, 50 conversion, decomposition, and recombination of hydrocarbon molecules for the production of an improved quantity and yield of gasoline over present known processes.

Other objects and advantages of this invention will be apparent during the course 55 of the following detailed description.

In the accompanying drawings, forming a part of this specification, and wherein similar reference characters designate corresponding parts throughout the several views, 60

Figure 1 is a sectional view, partly diagrammatic, showing the improved portions of the apparatus thru which the hydrocarbon material passes in the improved refining steps of this process. 65

Figure 2 is an enlarged fragmentary sectional view taken thru an improved portion of the apparatus which may be referred to as an expander, and wherein the hydrocarbon material in the vapor phase is treated 70 and heated in a novel manner for the production of a motor fuel.

Figures 3, 4, 5, and 6 are cross sectional views taken substantially on their respective lines in Figure 2 of the drawings. 75

Figure 7 is a diagram of a chart showing the relation and control of the percentage of unsaturates with respect to the temperature operation of the expander unit of this invention, and more particularly showing the independence, at certain expander temperatures, of the percentage of unsaturates with respect to the percentage of a certain quality of gasoline; this chart representing a typical mean operation of the 80 process. 85

Figures 8, 9, 10, 11 and 12 are diagrammatic representations showing the manner in which the improved process is operated to uniformly treat hydrocarbon vapors for 90 the most efficient conversion and recombination thereof to produce an improved proportionate yield and quality of motor fuel over present known processes; the views more particularly showing the relation in which the hydrocarbon vapors are subjected to the heating zones of certain heating elements about which the hydrocarbon vapors are free to travel; the different views more particularly designating typical circumstances of 95 operation of the system and process. 100

Figure 13 is an enlarged fragmentary sectional view showing anchor means for supporting certain heat conductors in the apparatus. 105

In the drawings, wherein for the purpose of illustration is shown a preferred embodiment of the apparatus by which the improved process is carried out, the letter A may generally designate the apparatus, portions of which are shown in the drawings and comprise a still B supported upon a fur- 110

nace construction C. An expander tank or receptacle D is supported upon a novel oven, furnace, or other foundation E preferably in such manner that products of combustion 5 may be received from the furnace C for also heating the expander D, and so that a fire may also be built beneath the expander, or other independent means used for heating the same than the furnace C. The still B has 10 a vapor flow line F connected therewith and with the expander D. Other portions of the apparatus are conventional, and may comprise dephlegmators; condensers; treating apparatus; separators; and the like.

15 In the preferred instance the vaporizer or still B is of the shell type. The initial vaporizer or still B may be such a type as will produce the vapors from petroleum in the order of their respective boiling points.

20 It is preferably of the horizontal type supported by the front and rear walls 15 and 16 respectively of the furnace C, and above the grate 16 of the furnace C in spaced relation therewith to provide a fire compartment 25 17 beneath the still B which may be of any approved character. The furnace C may be designed to provide an ash pit 18 therebeneath and the fuel used may be oil, gas, coal, or any other suitable heating medium, even 30 electrical.

The vaporizer or still B may be provided with any of the conventional controls, and these are necessary in order that the vapor may be in the best condition for reception in 35 the expander D wherein the novel process may be efficiently carried out without being subject to eccentricities due to incomplete or inefficiently vaporized products from the still. Intermediate its ends and on the top 40 thereof the still B is provided with a vapor dome 19 into which the vapor travels and flows into the horizontal vapor line F past a check valve 21 which prevents its return to the still.

45 The expander unit D is more particularly shown in Figure 2 of the drawings, and comprises a vertically disposed hollow cylindrical shaped shell or housing 30 including the cylindrical shaped side wall 31 having a top header or wall 32 of the disc type peripherally welded in place within the upper end of the cylindrical shaped body portion 30 and also including a disc-shaped bottom wall or header 33 peripherally welded in place 55 within the lower end of the body 31. The shell 30 is thus provided with a vertical substantially cylindrical shaped compartment 35 therein which is of uniform diameter from end to end throughout the vertical 60 height thereof.

Vertical tubes or other heating elements 36 are supported at their ends in the top and bottom plates or headers 32 and 33. In the preferred instance the heating elements 36 65 will be tubes, although they are referred to

as heating elements since it is entirely possible to form them of electrical resistance coils. In fact any elongated heating elements may be utilized which are in the same definite arrangement. The heating elements or tubes 36 at their upper ends each extend thru openings in the top plate or header 32 and in said openings are surrounded by soft metal or other sealing material rings 38, and the upper outer ends 39 of the said flues or tubes 36 are peened outwardly and over the upper surface of the top wall 32; as illustrated in the drawings, to provide a tight joint which will prevent the vapor leaking from the compartment 35 thru the joints of the flues at the plate 32. In similar manner at their lower ends the flues or heating elements 36 extend thru suitable apertures in the bottom wall 33 and also thru apertures in a centering disc 40 at the outer surface of the bottom plate or header 33; these lower ends of the flues being surrounded by means of ring-shaped washers 42 disposed in the said openings, and the lower extreme ends of the flues or tubes are outwardly peened at 43 in overlying relation on the lower surface of the centering plate 40, in the relation of parts illustrated in Figure 2 of the drawings, to provide a leak-proof joint for the vapors in the compartment 35 of the expander shell. The passageways 44, in case the heating elements 36 are tubular or flue-like in form, are of uniform diameter from end to end and open outwardly at the ends thereof at the outer surfaces of the end plates of the shell, and the heating medium is adapted to pass thru these passageways 44.

All of the heating elements or flues 36 are of the same diameter, lengths, and proportionate positioning with respect to the draft or source of heat. They are uniformly spaced exteriorly from each other within the shell compartment 35 in a somewhat staggered relation so that each one of said tubes will immediately face the space between an adjacent pair of the tubes. In this manner a typical example of the reaction thru which the vapors pass may consist of an arrangement of three tubes as illustrated in Figures 8 to 12 inclusive, surrounded by certain 115 heating zones, with a definite safety zone in the central space between these three tubes or heating elements, thru which the vapors pass in a definitely guided relation to enable the molecular conversion to expeditiously and efficiently take place in a manner which can be definitely ascertained and controlled, without the production of end point products.

While the dimensions and arrangement 125 of the expander shell and heating elements therein may vary considerably under different circumstances, in the refining plant at Fort Worth, Texas, and also at Ranger, Texas, expanders have been used utilizing a 130

three-foot diameter shell, fourteen feet in length, with two-inch interior diameter flues or tubes fourteen feet in length. This expander contained fifty-four of the two-inch tubes or flues. Of course expanders of different shell dimensions and tube dimensions may be provided under various circumstances as is readily apparent, without affecting the process or theory of invention.

Within the compartment of the shell 30 are positioned upper and lower baffle plates 45 and 46 respectively, located one-third the length of the compartment 35 in spaced relation from the respective top and bottom plates 32 and 33, so that the interior of the compartment 35 is divided into three spaces of equal height. These baffle plates 45 and 46, of course, have large openings therein for receiving the flues or heating elements 36 therethrough, and are also provided with smaller openings or perforations 47 thru which the vapors pass in their baffled relation from one section of the compartment to the other. The baffle plates are provided in order to interfere with the vertical mass movement of the vapors under treatment, in order that the vapor molecules will be most efficiently distributed about the heating flues or elements 36 in order to best and most efficiently come under the influence of the heat energy radiated to cause a uniform conversion and recombination of the vapor molecules.

Referring to the support of the expander shell 30 the furnace E is provided, of the Dutch oven type, including the base walls 50, having a frusto-conical supporting wall 51 at the top thereof, upon which the expander shell 30 is supported thru the intermediary of an insulating and protecting construction 52 which will be fully described hereinafter. The furnace E has heating communication thru a passageway 54 with the furnace compartment of the vaporizer or still B, so that the products of combustion therefrom may pass thru certain openings 55 in the furnace walls 50 and thence pass upwardly thru the furnace E into the passageways of the flues 36. The Dutch oven or furnace E is also arranged to independently heat the expander from fire box 50a.

The construction 52 preferably consists of a metal cylindrical shaped wall 57 having a bottom metal plate 58 welded or otherwise secured thereto. The plate 40 of the shell construction, above described, is annularly spaced at its outer periphery a short distance inwardly from the outer periphery of the shell wall 31, and in this space the upper marginal portion of the cylindrical shaped wall 57 is adapted to be received, to seat the lower marginal edge of the shell wall 31 on the top edge of the wall 57; the plate 40 thus being snugly received in the upper open

end of the cylindrical shaped wall or body 57, to act as a centering feature. Turn-buckle or clamping structures 60 are provided in connected relation between the wall 57 and the wall 31 of the shell 30, to securely and detachably clamp the shell 30 upon the construction 52 in a proper supported relation; any number of these turn-buckles or clamps 60 being provided circumferentially for the support of the shell upon the construction 52, as illustrated in Figure 2 of the drawings. When thus seated the wall or plate 40 is of course spaced from the lower plate 58 of the construction 52, and in this space directly upon the bottom plate 58 is disposed a thickness of insulating material 61 of any approved character. Within the space and in spaced relation above the insulation material 61 is disposed a preferably metal plate 63 which is peripherally welded in place to the wall 57, and on top of this plate 63 rests insulating material 64 of any approved thickness. The space 65 between the plate 63 and insulating material 61 is a dead air space to furnish the proper insulation for protecting the bottom plate or header of the shell construction, and between the top surface of the insulation 64 and the bottom centering plate 40 of the shell construction is also disposed a space 68 which may be termed a ventilating space, since the wall 57 of the construction 52 in confronting relation with the space 68 is provided with vent ports 70 annularly surrounding the wall 57, as illustrated in Figure 2 of the drawings. This construction effectively protects the bottom plate of the shell construction against deteriorating heating influences.

The heat from the furnace is properly conducted to the flues or heating elements 36 by means of auxiliary conducting flues 72 which are preferably cast iron. They are tubular in form and snugly extend thru openings provided in the plates 58 and 63 and the insulation material 61 and 64, and at their lower ends they extend to the outer surface of the plate 58 and are there peened over at 74 in a sealed relation; sealing rings 75 of some metallic sealing substance preferably sealing the joint of the said auxiliary heating flues 72 upon the plate 58, to prevent passage of heat exteriorly about said flues upwardly thru the plate 58. The said auxiliary heating flues or elements 72 at their upper ends are swedged and reduced at 77, so that they may be detachably fitted snugly into the lower ends of the passageways 44 of the heat conducting flues 36, in the relation illustrated in Figure 2.

As a means of preventing the dropping of the auxiliary flues or heating elements 72 it is preferred to provide bolts 78 in detachably supported relation upon the bottom plate 58 of the insulating construction 52,

which may be adjusted so that the heads 79 thereof will engage the peened outer flanges 74 of the said auxiliary flues 72, in order to hold them in place. This bolting construction may also be used for holding the ends of the flues or heating tubes 36 in place on the top and bottom headers of the shell 30, if desired.

Referring to the inlet and outlet of vapors with respect to the expander, and the vapor connection for the still or vaporizer B, the vapor flow line F is provided with a by-pass conduit 80 extending vertically downward and having a connection at 81 in the lower end of the expander shell 30 several inches above the bottom plate 33; the vapor inlet introducing the vapors into the shell compartment below the baffle plate 46. One or more of these inlets may be provided, but it is preferred to only provide one inlet. In the by-pass line 80 is provided a control valve 83, and in the vapor line F at the remote side of the by-pass conduit connection is provided a cut-off valve 84 which may be closed to direct all of the vapors thru the by-pass line and through the expander. Of course by closing the valve 83 the vapors thru the flow line F may be cut off from the expander.

In the top of the expander shell 30 at the diametrically opposed side from the inlet connection of the conduit 80 is an exit conduit 85 for exit of the converted and recombined vapor molecules; this connection communicating with the compartment 35 at the top thereof, several inches below the top header or plate 32, and in the space above the top baffle plate 45. In this conduit line 85 is provided a check valve 87 of conventional form, and the conduit 85 has a vertically extending drop connection 88 with the horizontal flow line F which leads to any suitable dephlegmating means or condensing apparatus, as well known to the art, and shown more particularly in my co-pending application above referred to.

In the connecting passageway between the vaporizer furnace and the expander furnace E is disposed a control damper 90. The upper end of the expander shell 30 may be stabilized by means of diagonal brace rods 91, which are received in suitable sockets 92 attached to the upper exterior end of the shell 30 and at their lower ends received in suitable sockets 93 supported on the top of the furnace wall construction illustrated in Figure 1 of the drawings. The heat or products of combustion as they pass from the tubes 36 are received in a space 94 above the top plate or header 32 and are guided by means of a frusto-conical hood 95 into any approved pipe or chimney. The furnaces of the vaporizer and expander are of course provided with suitable temperature recorders for determining the heat being applied to the

vaporizer and expander, and also recording thermometers of approved character are associated with the vaporizer or still and the expander shell for the purpose of recording the temperature of the constituents within the respective still and expander at predetermined locations. Other approved instruments may be supported by the vaporizer and expander, for recording and determining the various characteristics of the initial product and vapor product during the process of treatment thereof in any of its stages.

Referring to the operation of the invention the petroleum product is placed in the still B and there vaporized at suitable temperatures in order that the vapors of the petroleum pass off in the order of their respective boiling points. The speed of operation of the vaporizer for the improved process is substantially three times that permissible under normal skimming operation, with good separation. This speed of operation is due to the rearranging effect upon the original vapor molecules, within the expander, to produce at a high speed of operation a very much larger percent of the gasoline fractions than are conventionally produced.

The vapor passes thru the by-pass conduit 83 into the lower end of the expander chamber or compartment. The design of the tubular heating elements of the expanded provides a means whereby the predetermined necessary amount of heat, which may be developed in any suitable manner, may be conducted with precision and exactness into a mass of hydrocarbon vapors with equal distribution of radiant heat energy throughout the mass. The vapor entering the inlet port at the lower end of the expander shell immediately contacts with the heated flues or tubes nearest the inlet port or ports, as the case may be, and receiving heat energy from the heating elements 36 the vapors will rise in spiraled relation about the heating elements 36 in a vertical mass movement towards the exit or outflow line 85. Owing to the velocity of flow of the incoming vapors at the inlet port or ports, the vaporized material passes the heating elements next immediately adjacent the ports to the opposite side of the shell and contacts with the remainder of the flues within the lower chamber of the expander below the lowermost baffle plate 46. The distribution of vapors is assisted by the positioning of the perforated baffle plates 45 and 46, which interfere with the mass movement of the vapors, and this interference with the natural vertical mass movement of the vapor molecules, in conjunction with the influence of the heat energy radiating from the heating elements combine to produce and insure the continuance of a positive "turbulent flow" of vapors thru the expander. Within

the expander the influence of the heat on the vapor molecules will produce a thermo-chemical reaction, the theory of which will be described more in detail hereinafter, so that the vapors are treated in successive stages throughout the height of the expander shell. The molecules are of high molecular weight as they enter the expander and are subject to a mechanical expansion due to the release of space restriction, which is augmented by the heat treatment to further cause an expansion thereof. At a location in the lower portion of the expander compartment the vapor molecules are subject to an initial conversion. Above this the conversion of the vapor molecules is being finished and recombination of the vapor molecules has started. Above this recombination of the vapor molecules has been efficiently carried out to form molecules of low molecular weight. The thus recombinied vapor molecules are then permitted to exit thru the line 85 where they are subject to further conventional dephlegmating and condensing treatment for the production of gasoline.

It is well known to those skilled in the art that success in the vapor phase production of gasoline depends upon careful attention to details of design and operation. This has been found especially true in vapor phase cracking processes. Conventional cracking processes using the vapor phase are carried out by the exterior heat treatment of the hydrocarbon vapors which are carried within tubes or coils having a definite space restriction. These conventional vapor phase treatments carried out within tubes or flues compel the vapor to have a high velocity and a very turbulent flow. It is notorious that such conventional processes produce gasoline having large proportion of end point compounds, with a lack of proper proportion of low boiling point hydrocarbons. In these conventional vapor phase cracking processes the unsaturation percentage is notoriously uncontrollable, so that to economically produce a proper yield of gasoline requires that the olefin content thereof be irregular, and in many instances the motor fuel is commercially unusable or inefficient.

It has heretofore been thought that hydrocarbon in the vapor phase would decompose better in tubes than in an unrestricted space, but this is only true because no efficient means for carrying out the thermo-chemical treatment within the space had been provided.

An outstanding feature of the vapor phase treatment of hydrocarbons of this invention, over the conventional vapor treatment within tubes or coils, is the facility with which the heat reactions may be controlled. The actual heat radiated within the tube or coil

system of vapor treatment is either entirely too great or too small in quantity and it is notoriously difficult to attain a mean control. If the flow within a restricted tube be slowed sufficiently to enable the proper decomposition, the molecules immediately next to the interior walls of the tube will be decomposed too rapidly and result in end point products. Now if we assume an increased flow of the vapor thru a tube or vapor coil, the molecules no longer move in straight line, but have a turbulent motion or flow which produces a centrifugal mass motion of the vapors, thereby continually forcing the mass of vapors towards the inner wall of the flue where the tube is hottest so that they are subjected to an excessive application of heat energy and result in end point products the same as in the case where the velocity is slowed in the pipes or tubes to produce a straight line flow. With the conventional vapor phase treating tube or coil, each tube or coil in effect is a unit in itself, and it is not reasonable to assume that any number of such tubes can have identical effects upon vapors being conducted thru them, since the reaction within each tube or coil is isolated from the reaction within all other tubes or coils of the system. Uniformity under commercially practical conditions cannot exist and has proven not to exist with the conventional tube or coil vapor phase refining or treating systems, since the conditions governing heat transfer, radiation, conduction, convection, intensity of heat, and heat absorption by the vapors cannot be accurately and efficiently controlled in conventional processes heretofore developed.

Referring now to a comparative explanation of the reaction, flow, and treatment of the vapor particles in the improved expansion process, with respect to the conventional vapor treating processes above outlined, the vapors as above mentioned enter the lower end of the expander compartment and pass upwardly in a spiral relation about the heating elements. The flow of the hydrocarbon vapors upwardly thru the expander will be a turbulent flow even at the slowest speed commercially practical, but the physical action of the vapors will be directly opposite to the type of treatment which is accorded vapors within the conventional cracking tubes and coils. The effect of the reception of sufficient heat by the molecules causes an increase in their kinetic energy, resulting in:—(1) creating an increase in the vertical velocity of the spiral movement about the heating elements; (2) creating a centrifugal force which moves the molecules away from the heating elements, and not toward the source of heat as is the case with the conventional cracking tubes. This transverse movement of the

molecules away from the heating elements is toward what may be aptly characterized "safety zones", or zones of low heat intensity which are graphically shown in typical 5 occurrences in Figures 8 to 12 inclusive. In each of these figures is shown a series of three of the heating tubes or elements characterized as 36^a, 36^b and 36^c. This is the typical occurrence in which the uniformly spaced flues are arranged in the expander, and the thus triangular spaced arrangement of heating elements provides a central substantially triangular shaped safety zone or space 110 arranged in substantially vertical 10 parallel relation throughout the length of the spaced heating elements, and which safety zone plays a very important part in the conversion and recombination of the vapor molecules to produce the increased 15 yield of hydrocarbon product at comparatively high speed of operation of the unit. As is designated in Figure 9 surrounding each of the heating tubes or elements 36^a, 36^b, and 36^c, are the annular zones 111, which 20 may be increased in depth or degree of intensity by regulating the temperature of the heating elements. The intensity of these heating zones to carry out the proper reaction may be varied so that the depths of 25 the said heating zones 111 operate to increase or decrease the cross area of the low heating zones or draft ways 110 between and along the said flues or heating elements. The intensity may be increased as illustrated 30 in Figure 10, over the illustration in Figure 9, until the heat radiating zones 111 are in intimate contact, which is probably the most efficient circumstance under which the process is operated so as to provide transversely closed safety zones of triangular shape. The intensity of the heating zones 35 may be increased until they overlap as illustrated in Figure 11 and the safety zone will be completely eliminated, and the overlapping of the intense heating zones 111 will cause the hydrocarbon vapors therein to become decomposed into end point products. In Figure 12 is illustrated an extreme example 40 showing the results of carrying the heating to a point of excess so that the vapor will be decomposed into end point products of an undesirable nature. In Figure 8 is illustrated in dotted lines a subdivision of the heating zones into a plurality of heating zones 111^a, 111^b and 111^c of successively decreasing intensity from each of the heating flues or elements, and in these various concentric or otherwise positioned heating zones the hydrocarbon vapors are treated to best 45 carry out the reaction for the speedy production of an increased yield of desirable hydrocarbon products.

The movement of the molecules due to the increase of energy is from the heating elements towards the safety zones or central

spaces 110, and the apparent results upon the vapor molecules because of these zones 110 are:—(1) The molecules which have not recombined after the initial treatment into a configuration which will be stable under the conditions then effective, will be, owing to their slower kinetic movements, exposed to the source of heat until such combination does occur. That is, the molecules of high molecular weight and greatest specific gravity will lag behind in the safety zones, finally contacting with the radiating zones, while the molecules which have formed into a configuration which is stable under the conditions of operation established are sufficiently decreased in specific gravity to permit of their increased velocity in a vertical upward movement. These stable molecules are not susceptible to the heat radiating from the flues or heating elements 50 from the standpoint of affecting their configuration, but are susceptible to the spiral travel of the heat radiated from the flues, to accelerate their movements out of the expander, and hence they move into the safety zones where the least thermo-chemical activity takes place under normal operation, thence into the condensing system. This condition inheres in the graphic example illustrated in Figure 10.

If the concentration of vapor is below the point at which the quantity of vapor traversing the heating zones is insufficient to dissipate the quantity of heat energy radiated, or if the radiation of energy is increased without a corresponding increase in vapor concentration, the effect will be to cut down the area of the safety zones until a point is reached where the radiation of any flue overlaps to varying degree the radiations of adjacent flues as is graphically illustrated in Figures 11 and 12. This radiation overlap when progressively increased, decreases the stability of the vapor product, introduced into the expander, until a point is reached at which the only stable system is that which consists of end point products such as carbon and fixed gases. The control of this situation will be hereinafter more fully commented upon.

The heating elements or flues are of exactly the same length, diameter, and proportionate positioning with respect to the draft or source of heat, so that the radiation of supplied heat energy into the mass of vapors must necessarily be approximately the same throughout the entire length of each tube or heating element of the system. As a consequence with a positive control of the vaporizer or still's rate of distillation, and of the quantity of heat being generated and supplied the heating elements or flues, it is not difficult to have a positive control of the heat effect upon the vapors subject to treatment by this process. Positive and uniform heat

control in commercially practical manner has been proven during experimental and commercial tests of the process.

The normal rate of flow of vapor from the still or vaporizer to the expander, determined as the mean rate to be used, is admitted to the expander when the latter is only a few degrees in temperature ahead of the temperature of the incoming vapors.

11 The temperature of the expander is then increased to the maximum gasoline yield without reaching the critical carbon and gas production point possible for the type of oil being treated. Under these conditions the

13 radiation of heat from the heating elements or flues is restricted considerably, and the zones of greatest chemical activity shown in Figure 9 are small in proportion to the total area occupied by the vapors. As the quantity of radiant heat energy transmitted into the vapors is increased the fields of radiation and intensity of chemical effect grow, until the relation illustrated in Figure 10 is reached where the radiations have become 25 sufficiently strong to touch the thermo-chemically effective radiating fields of adjacent flues or heating elements. This condition results in the production of the maximum percent yield of gasoline without end point 30 products forming, and is considered the normal operating condition as above mentioned.

As to the practical operating conditions, the still is charged, as for a batch run, and fired when two petcocks by gauge column have 35 been charged to it, raising the temperature at the rate of about fifty to sixty degrees F. per hour, until at a temperature of about 190° F. when the fire should be slakened to about 20° F. per hour rise, until the oil has 40 passed the temperature at which it is likely to "puke" (212° F.-225° F.). The still temperature is now raised at about 40° F. per hour until the still is "over". Just prior to this steam should be turned into the expander 45 thru a steam conduit 120 which has connections with both the vaporizer and expander, and an exterior source of steam, and the steam is fed into the expander in suitable quantities at 75 pounds on a two-inch valve, 50 and then the expander is heated by means of one burner to the same temperature as the still or vaporizer B. The still is fired until streams are running about 15 to 20 barrels per hour, and the start pump charging semi- 55 continuous. When the vaporizer or still has settled down to steady continued streams of about 15 to 20 barrels per hour the vapor from the still is by-passed into the expander, with the latter heated at about 100° F. 60 higher temperature than the still. The straight away valve 84 is left wide open until the expander has taken the vapor correctly, and then the straight away valve 84 is slowly closed until all of the vapors are 65 passing thru the expander conduit 83 into

the lower end of the expander. At about this time, or as soon as the vapors have passed onto the tail house the steam charging thru the expander is cut out with the exception of a small plume about 15 to 16 inches long, 70 which should be left in the expander until conversion of the molecules has set in, as shown by test cuts of the tail house streams, and then the steam should be cut out altogether from the expander. 75

In case of overheating of the expander, firing should be reduced even though the temperature shown by the recorder within the expander is not above the regular running temperature of 670° F. to 800° F. This 80 overheating is probably due to a too small feed of vapors coming over into the expander for treatment, and will be further evidenced by the character of distillates 85 coming over, which will be very dark brown to black in color, and carry a large amount of granular carbon in suspension. The condition will be corrected by reducing the expander fires, but not necessarily the recording temperature within the expander if it 90 is less than the specified regular running temperatures for the material being treated.

A mean low temperature for any particular oil may be empirically determined, and should be increased on the expander as soon as the expander settles down to handling the vapors steadily to the maximum temperature for that specific oil. 95

In commercial practice the maximum temperature allowable in expander for any rate 100 of vapor supply from any type of petroleum oil, is that temperature, determined by experimentation, at which a small amount of granular carbon is suspended in the streams passing thru the receiving house. 105

The following control methods are effective under various conditions for regulation of carbon and end point gases:

The amount of carbon coming over may be reduced to zero or just within commercial 110 limits by:

1. Reducing the temperature in the expander. This may be done by slackening the fire in the expander fire box.

2. By increasing the rate of feed of new 115 oil to the vaporizer so as to provide a lower boiling fraction which will distill at the temperature of the still then effective.

3. By increasing the rate of distillate from the still or vaporizer by increasing the 120 fire under the same.

A practically uniform and permanent adjustment may be secured by the immediate, careful, and repeated, but very slight reduction of the expander fire at the first appearance of carbon, during a period of about thirty minutes, in order to bring the expander into synchronism with the rate and volume at which the still is producing and 125 supplying vapor. 130

No liquids are contained in the expander during operation, and in this connection the expander may be provided with a suitable drain trap (not shown) for removing any liquid which in the starting and stopping of operation of same may collect therein.

From the foregoing it is apparent that synchronism of the vaporizer and the expander still means that just the right velocity and volume of untreated oil vapor is supplied from the vaporizer to the expander still so that the heat generated within the expander fire box may, by means of the novel heating element arrangement in the expander, be applied to the vapors with a thoroughness and rapidity that will permit the larger part of the energy being so developed and supplied, to cause the physical and chemical changes necessary for the maximum conversion of the initial vapors into gasoline, and at the same time have a minimum production of end point products commercially allowable.

There should be just enough steam supplied to the vaporizer or still to agitate the oil upon its bottom plates according to general practice, and none should be supplied to the expander still direct except as above mentioned for starting the same, and when shutting down for any reason to remove vapors.

The theory of molecular conversion follows well known laws. The re-association of particles which have been dissociated by the action of the heat is due to the attraction or energy of the same, and it is due to the favorable mechanical arrangements of this apparatus, and the novel spaced relation of the heating elements of this invention, that enables the proper dissociation and chemical reaction and the efficient re-association or combination into the new complex hydrocarbon molecules which will remain stable under practical conditions of operation such as are herein outlined.

In Figure 7 is graphically shown a chart defining the relation of the percent of unsaturates to the percent of yield of 450° F. end point gasoline. This chart shows that the percentage of unsaturates is controlled independent of the percent of yield and this is very important in view of the modern practice to definitely ascribe a mean percentage of unsaturates to motor fuel oil, as necessary for maximum efficiency in use. The unsaturates are controlled by increasing at a given temperature, the volume of vapor passing thru the expander still in a given length of time. The vapor may be all oil vapor, or partly oil and partly steam. Both the yield of gasoline and unsaturates are controlled independent of each other, as above pointed out by changing the quantity of heat energy radiated from the flues and imparted to the system of vapors; by changing the quantity

of steam in the expander; and by changing the quantity of oil vapors fed to the expander in a given time. This control would not be commercially feasible in the absence of the improved arrangement of penetrating the vapor space by means of a plurality of uniformly spaced heating flues or elements to provide heating zones of controllable varying intensity.

From the foregoing description of this invention it is apparent that a novel process of refining hydrocarbon products has been provided, which includes a series of zones of thermal-radiation which are of least thermochemical effectiveness intermediate a plurality of heat radiating zones, wherein are most efficiently removed the desired products of reaction before the time factor can cause their decomposition into end point reaction products. In this manner the yield of motor fuel and unsaturate percentages may be controlled efficiently for the production of a better motor fuel having a high compression ratio, and of a greater yield than is proportionately possible with present known vapor phase refining, treating and cracking processes.

Various changes in the steps of the process and the rearrangement of mechanical means by which the process may be effected, may be made to the invention herein shown and described, without departing from the spirit of the same or the scope of the claims.

I claim:

1. That process of refining hydrocarbons in the vapor phase which consists in feeding the hydrocarbon in its vapor phase vertically thru a space pierced by a plurality of heat radiating zones which heat the vapor to substantially the same intensity so that each thermo-chemically effective vapor conversion zone substantially abuts in unobstructed and non-overlapping relation with the outer portions of the like adjacent heating zones.

2. That process of refining hydrocarbons in the vapor phase which consists in feeding the hydrocarbon in its vapor phase vertically thru a space pierced by a plurality of heat radiating zones which heat the vapor to substantially the same intensity so that each effective vapor conversion zone substantially abuts in a non-overlapping relation with the outer portions of the like adjacent heating zones, the heating zones being arranged in spaced relatively unobstructive relation so as to provide vertical zones of lower heat intensity between the heating zones.

3. That process of treating hydrocarbons which consists in feeding the hydrocarbon in its vapor phase thru a vertical compartment which is pierced by a plurality of substantially vertically disposed heating elements, the heat radiations of which are such as to produce annular heating zones thereabout of a predetermined thermal intensity which

cause a decomposition of the initial vapor product therein, the heat intensity of the zones being so regulated that outer boundaries thereof beyond which decomposition of the vapor is not possible will substantially abut with respect to each other in a non-overlapping relation with like adjacent heating zones.

4. That process of refining hydrocarbons which consists in passing a hydrocarbon vapor into an expansion area and heating the vapor by a plurality of vertically disposed spaced heating elements which are heated to such a degree that the same will externally radiate heat in annular zones about the heating elements until the heated zones are in substantial contact at a predetermined temperature determined by the temperature at which the vapor molecules may be favorably decomposed.

5. That process of refining hydrocarbons which consists in passing a hydrocarbon vapor into an expansion area, heating the vapor by a plurality of vertically disposed spaced heating elements which are heated to such a degree that the same will externally radiate heat in annular zones about the heating elements until the heated zones are in substantial contact at a predetermined temperature determined by the temperature at which the vapor molecules may be favorably decomposed, said heating elements being arranged so that the heating zones provide intermediate zones between the heating zones which are of less thermo-chemically active temperature than the above predetermined temperature, and wherein the hydrocarbon vapors may pass in combination after treatment in the various adjacent heating zones.

6. That process of cracking hydrocarbons which consists in feeding the hydrocarbon in vapor phase in an undivided mass into a vertically arranged conversion area wherein the vapor travels from the bottom to the top of the area and within said conversion area thermo-chemically treating the vapor during its length of travel thru the conversion area by a plurality of vertically arranged heating zones disposed in a transverse triangularly laterally unobstructed arranged relation.

7. Apparatus for the treating of hydrocarbon products comprising a vertically disposed shell having a compartment therein, spaced top and bottom plates for the shell, flues connected at their upper and lower ends in said upper and lower plates each having passageways therethrough opening at their ends exteriorly of their respective plates and exteriorly of the compartment of the shell, means for passing a hydrocarbon vapor into the lower end of the shell com-

partment and causing it to exist at the upper end of said compartment, heat insulating means for the lower plate of said shell, means extending thru said heat insulating means for causing heat to travel thru said flue passageways, said last mentioned means including a plurality of auxiliary flues having the upper ends thereof detachably fitting into the lower ends of the passageways of the first mentioned flues of the shell.

8. Apparatus for the treatment of hydrocarbon products comprising a vertically disposed expander tank having a compartment therein and including a bottom, tubes extending vertically through the tank having passageways therethrough opening on the bottom of said tank, a casing connected with the tank therebelow having transverse perforations therethrough adjacent the bottom of the tank, an insulating plate mounted in said casing in spaced relation below the bottom of the tank, and flues extending through said insulating plate to the bottom of said tank having passageways therethrough aligning with the passageways of the tubes of said tank for conveying products of combustion from below the insulating plate into the tubes in the tank, the openings in said casing opening directly into the space between said insulating plate and the bottom of said tank.

9. Apparatus for the treatment of hydrocarbon products comprising a vertically disposed expander tank having a compartment therein and including a bottom, tubes extending vertically through the tank having passageways therethrough opening on the bottom of said tank, a casing connected with the tank therebelow having transverse perforations therethrough adjacent the bottom of the tank, an insulating plate mounted in said casing in spaced relation below the bottom of the tank, flues extending through said insulating plate to the bottom of said tank having passageways therethrough aligning with the passageways of the tubes of said tank for conveying products of combustion from below the insulating plate into the tubes in the tank, the openings in said casing opening directly into the space between said insulating plate and the bottom of said tank, a second insulation plate in the casing in spaced relation below the first mentioned insulating plate having the flues extended across said space into the last mentioned plate for the purpose of directing products of combustion from beneath the last mentioned plate into said flues and thru the tubes of said tank, the space between the first and second mentioned insulation plates being a sealed dead air space.
